2.13 : Reference view of state in use

The solid lines form part of the claimed designs; the broken lines depict unclaimed portions of the biosignal detector and form no part of the claim, additionally, the broken lines forming the outer edges of a wearer in Figs. 1.13 & 2.13 depict environmental subject matter only and form no part of the claimed design; the biosignal detectors of designs 1 and 2 can detect biosignals (e.g., electrocardio signals, mastication signals) using the electrodes.
